UNITED STATES PATENT OFFICE.

CHRISTOPHER J. ROACH, OF MIDDLETON, CONNECTICUT.

CHISEL-HANDLE.

1,268,871.

Specification of Letters Patent. Patented June 11, 1918.

Application filed September 17, 1915. Serial No. 51,197.

To all whom it may concern:

Be it known that I, CHRISTOPHER J. ROACH, a citizen of the United States, residing at Middletown, in the county of Middlesex and State of Connecticut, have invented certain new and useful Improvements in Chisel-Handles, of which the following is a specification.

My invention relates to improvements in chisel handles, particularly of the type having the blade separable from the handle, and the object of my improvement is simplicity and economy in construction and convenience and efficiency in use, and while primarily adapted for use with chisel blades it is understood may also be used for some other form of blade.

In the accompanying drawing:

Figure 1 is a side elevation of my improved chisel handle and a chisel blade.

Fig. 2 is an end elevation of the same.

Fig. 3 is a sectional view, on an enlarged scale, on the line $\alpha\alpha$ of Fig. 2, the blade being in side elevation and in part broken away.

Fig. 4 is a similar view of a modified form of handle.

Fig. 5 is a side elevation of part of the same.

Figs. 6 and 7 are views corresponding to Figs. 4 and 5 of another modified form of handle.

My improved chisel handle comprises a generally cylindrical body portion 10, which may have any desired form exteriorly, suitably to serve as the handle proper, and a handle extension 11 at the front end having means for removably receiving the blade 12, and preferably has at the rear end an enlarged head 13, and the said structure is provided with a bore 14 that extends from end to end thereof.

The portion of the bore 14 in the extension 11 is in the form of a tapered socket 15 which is a fit for and suitable to receive a tapered head 16 on the shank of the blade 12.

Adjacent the small end of the socket 15 the body portion 10 is provided with a diametral slot 17 extending through both side walls and the tapered head 16 is of sufficient length to extend part way across the said slot 17, suitably to be engaged with a tapered key for forcibly removing the blade 55 from the handle as is common in some

forms of tools, as for removing chucks from a drill press spindle.

At the rear end of the handle structure the bore 14 is closed by a plug 18 made of some proper form of cushioning material, such as wood, fiber, or raw-hide, which preferably extends a short distance outwardly of the enlarged head 13, as shown at 19, to serve as a hammer head.

The seat for the plug 18 comprises a taper form 20 at the inner end of appreciable length, a flat or annular portion 21 adjacent the junction of the enlarged head 13 and the handle proper 10, and a second tapered portion 22 within the enlarged head 13 and extending from the annular portion 21 to the extreme outer end, and the plug 18 is of suitable form to fit the seat as described.

It will be noted that the form of the seat for the plug 18 is such as to permit the removal of the said plug from the handle structure. Such removal is facilitated by first removing the blade 12 from the handle structure and then inserting a tool or rod in the bore 14 whereby force may be applied to the plug 18 for driving the same from its seat.

Some other form of seat may be provided that will permit of removal of the plug in the manner described, as for instance, the same may be made with a continuous taper, such as the tapered portion 20 of suitable length.

The construction described permits of having an enlarged head 19 on the plug 18 and at the same time having the plug extend well into the handle body, and without undue enlargement of the said handle body 10.

In the modification shown in Figs. 4 and 5 the slot 17 is omitted and the means for removing the blade 12 is as follows:

It will be noted that the blade 12 is provided with a laterally extending shoulder 100 at the base of the tapered shank 16.

The inner end of the extension 11^a in which the tapered socket 15 is provided is exteriorly provided with a screw thread 24. Engaged with the said screw thread 24 is a sleeve-like nut 25 having at the front end an inwardly directed, annular collar 26, which is positioned between the platform 23 and the opposed end of the extension 11^a.

The shank extends beyond the socket 15 110

sufficiently to provide free space between the shoulder 23 and the end of the extension 11^a as shown at 27 to house the collar 26 and permit a slight longitudinal movement 5 thereof.

Normally the nut 25 will be screwed on the thread 24 so that the collar portion 26 abuts with the end of the extension 11^a. When it is desired to remove the tool 12 10 the nut 25 is turned so as to be moved off from the threaded portion 24, carrying the collar portion 26 along until the same abuts with the shoulder 23, after which by applying force to the nut 25 the tool will be 15 forced from engagement with the socket 15.

In the modification shown in Figs. 6 and 7, the extension 11^b is in the form of a plurality of spring jaws 31, extending longitudinally along the tool shank 16^b, which 20 latter may be cylindrical in form, and having the exterior screw thread, as shown at 28. The extreme end portion 29 is tapered.

The sleeve 25^a is threaded interiorly for the major part of the length, and at the 25 front end portion is tapered as shown at 30, suitably to cooperate with the tapered or conical end portion 29 of the jaws 31 so as to effect a clamping of the shank 16^b.

That is to say, the bore 33 in the end portion 32 of the sleeve 25^a is in the form of a cone, having a short and steep taper.

I prefer to have the said end portion 32 extend beyond the jaws 31 so that the same will engage with the shoulder 23 so as to 35 force the same away from the jaws 31 after the sleeve 25 has been moved away from the clamping position in case the jaws may become set against the shank, thus operating after the manner of the collar 26.

40 The extension 11^b of the handle and the sleeve nut 25^a cooperate as chuck members to engage and disengage the tool handle, and the nut 25^a serves as a backing off nut to force the tool shank from the position of 45 engagement with the jaws after the clamping pressure on the said shank has been released by the backing away of the conical portion 33 of the bore of the sleeve nut 25^a from engagement with the tapered end portion 50 of the jaws 31 or extension 11^b. The sleeve nut serving accordingly both as a chuck member and as a backing-off nut.

The plug 18 as shown has an axial bore 34 that is appreciably smaller in diameter 55 than the inner end face of the tapered head 16 of the tool 12. A tool of suitable form or a rod may be inserted through the said bore 34 and engaged with the end face and will thus serve as a means for driving the 60 tool 12 from the tapered socket 15.

I claim as my invention:

1. A handle for a chisel or similar tool comprising an elongated structure of tubular form, the body portion constituting the major

portion of the length, being of suitable size 65 and having a suitable exterior formation to serve as the handle proper, and having an open bore, the end portions being each provided with a tapered socket, connecting with the said bore, and a plug of cushioning material being seated in one of the said sockets and having an axial bore, whereby a tool may be inserted through the said axial bore for removing a tool seated in the other of the said sockets. 70

2. A handle for a chisel or similar tool comprising an elongated body portion suitable to serve as the handle proper, one end having a tapered socket for removably receiving the shank of a tool and having means 80 for effecting the removal of the said tool from the said socket, the other end having a tapered socket for removably receiving a plug of cushioning material, and the said body portion having a longitudinal bore 85 that opens at the ends into the said sockets.

3. A handle for a chisel or similar tool comprising an elongated structure having a bore extending continuously therethrough, means for removably receiving a tool shank at one end of the said bore, the other end of the said bore being in the form of a seat, a cushioning plug fitting and engaged with the said seat, and the said seat comprising at the inner end an elongated tapered 90 portion, suitable for serving as a holding portion, the outer end of the said seat being approximately cylindrical, suitably to serve as a ferrule in engagement with the said plug, and an annular step connecting the 95 said tapered portion and ferrule, suitable for serving as a seat proper in engagement with the said plug.

4. A handle for a chisel or similar tool comprising a body portion serving as a handle proper, a socket member at one end of the said body portion having a socket for receiving a tool shank and having means for ejecting the said shank therefrom, a second socket member at the other end of 105 the said body portion having a socket for receiving a cushioning member, and the said body portion having a bore connecting the said sockets, whereby after the said shank is removed from its socket means may be inserted through the said bore for forcing out the said cushioning member from the 110 said socket member.

5. A handle for a chisel or similar tool comprising an elongated structure having a 120 bore extending continuously therethrough, means for removably receiving a tool shank at one end of the said bore, the other end of the said bore being in the form of a seat, a cushioning plug fitting and engaged with the seat, and the said seat comprising at the inner end an elongated tapered 125 portion, suitable for serving as a holding

portion for holding the said plug in position, the outer end of the said seat being approximately cylindrical, suitably to serve as a ferrule in engagement with the said plug, 5 and an annular step connecting the said tapered portion and ferrule, suitable for serving as a seat proper in engagement with the said plug.
